UNITED STATES PATENT OFFICE.

CHARLES FREDERICK HOOFER, OF CHICAGO, ILLINOIS.

CUP-PISTON CONSTRUCTION FOR LUBRICATING DEVICES.

Application filed November 27, 1925. Serial No. 71,746.

My invention relates to improvements in cup piston constructions for lubricating devices, and it consists in the combinations, constructions, and arrangements herein described and claimed.

The principal object of my invention is to provide a cup piston construction having a resilient cup and an interior expander therefor, and in which the piston expander substantially supports the cup piston upon its base and presses the lips of the cup piston against the walls of the cylinder.

A further object of my invention is to provide a device of the type described in which the amount of time taken for manufacturing the device is cut down to a minimum, because the follower cap can be screwed down as tightly as possible, and when so tightened will exert the required amount of pressure upon the cup piston.

A further object of my invention is to provide a device of the type described in which novel means is provided for permitting the follower cap to be screwed down tightly into place to clamp the cup piston to the rod, this means preventing the cap from shearing the cup piston.

A further object of my invention is to provide a device of the type described which has novel means for preventing further movement of the follower cap when the cap has exerted the required amount of pressure on the cup piston, whereby a uniform product is assured.

Other objects and advantages will appear in the following specification, and the novel features of the invention will be particularly pointed out in the appended claims.

My invention is illustrated in the accompanying drawings, forming part of this application, in which—

Figure 1 is a vertical section through the device, and

Figure 2 is an enlarged view of a portion of the device partly in section.

In carrying out my invention, I provide a casing 1 for holding a lubricating fluid. The fluid is admitted to the casing through a door 2 and passes through a screen 3 before it is received in the casing. A drain plug 4 is provided for the casing.

A plurality of plungers 5 are mounted in the casing 1, and I have shown one of these plungers in Figure 1. Each plunger carries a piston at its upper end, and the novel de-

sign of this piston construction is clearly shown in Figure 2. A base 6 is screwed down upon the threaded portion 7 of the plunger rod 5, and this base is provided with a flange 8 for a purpose hereinafter described. A resilient cup 9 is mounted upon the base 6 and bears against the flange 8. The thickness of the wall of the cup is slightly greater than the height of the flange 8, and it will therefore appear that the bottom of the cup will extend slightly above the top of the flange. I next dispose what I term a metal expander 10 in the resilient cup 9. This expander conforms to the interior of the cup 9, and is provided with an inwardly extending flange 11 for overlying the top of the flange 8. The portion of the expander bearing against the inner periphery of the cup 9 is cut up into a plurality of resilient fingers 12. These fingers are for the purpose of normally expanding the cup 9, as will be hereinafter described.

The cup 9 and the expander 10 are locked in place by means of a follower cap 13. The side wall 14 of the cap is spaced from the inner surfaces of the fingers 12, thus permitting the compressed air to force its way down into the interior of the cup. The cap 13 when screwed into position forces the flange 11 down upon the flange 8, and in doing so causes the flange 11 to slightly squeeze the portion of the cup 9 disposed between the flange 11 and the shoulder 15 of the base 6. It will be seen that the cap may be screwed tightly into place, and yet will have no tendency to shear the cup 9. This is due to the fact that there is an all-metal connection between the cap 13 and the base 6. The wall of the cup-shaped member 9 is made of a predetermined thickness, and this thickness is sufficient to cause the flange 11 to slightly squeeze the wall when the flange is locked in place by the nut 13.

It will be noted from Figure 1 that the lower end of the plunger rod 5 is provided with a plunger head 16. A valve 17 is screwed into this plunger head, and this valve is provided with a tapered portion 18 adapted to seat against a tapered portion 19 to limit the movement of the plunger rod 5 away from the bottom of the casing, and to provide a liquid-tight closure between the liquid in the casing and the outlet nipple 20. The spring 21 extends the entire dis-

tance of the plunger rod and bears against the outlet plug 22 and the base 6.

From the foregoing description of the various parts of the device, the operation thereof may be readily understood. In operation air is admitted to the compartment 23 in the manner set forth in my co-pending application, Serial No. 718,341, filed June 6, 1924. As stated in my co-pending application, this air will force the plunger rod 5 downwardly, and will also flow through the bore of the plunger rod. Figure 1 shows how the tapered portion 18 prevents the top of the follower cap 13 from contacting with the screw plug 24. This construction permits the air to pass through the passageway 25 and into the bore of the plunger rod 5.

During the downward movement of the plunger rod 5, the oil in the recess 27 passes into the outlet nipple 20, and this quantity of oil is then conveyed to the part to be lubricated by the compressed air.

In the first part of the specification, I pointed out the advantage of providing an all-metal connection between the follower cap 13 and the flange 8 of the base 6. This construction permits the follower cap to be screwed tightly down upon the flange 11, thus bringing the flange into contact with the top of the flange 8 and causing the flange 11 to squeeze the cup 9. The wall of the cup 9 is made of a predetermined thickness and the flange 8 permits the required amount of pressure to be exerted upon the expander to squeeze the wall of the cup 9 between the expander and the shoulder 15, and then prevent further movement of the follower cap 13 toward the base 6. In this way, the workman assembling the device can screw up the follower cap as tight as possible without the possibility of shearing the cup 9. At the same time, the cup 9 and the expander 10 are locked in place and provide a leak-proof connection between the follower cap 13 and the base 6.

I claim:

1. In a device of the type described, a plunger rod, a base, a cup mounted on said base, an expander for said cup, and means for forcing said expander into contact with said base, said cup being clamped between said expander and said base, said base deter-

mining the amount of pressure exerted by the expander upon the cup.

2. A device of the type described comprising a plunger rod, a base mounted on said rod and having a flange, a cup carried by said base, an expander carried by said rod and bearing against said flange, and a follower cap secured to said rod for forcing said expander into contact with said flange, said cup being slightly squeezed between said expander and said base, said flange limiting the amount of force exerted by the expander upon said cup. 65

3. In a piston construction, a plunger rod, a base carried by the plunger rod, a resilient cup carried by the base, means for clamping the cup to the base, and means for preventing the shearing of the cup by the clamping 70 means.

4. In a piston construction, a plunger rod, a resilient cup, means for clamping said cup to said rod, and means for limiting the force of said clamping means to prevent 75 said clamping means from shearing the cup.

5. A cup piston construction for lubricating devices comprising a supporting member having a threaded portion, a base carried by said threaded portion and having a centrally disposed annular flange, a resilient cup disposed on the base and having a central opening arranged to receive said annular flange, an expander having a portion disposed in engagement with said 80 flange and being arranged to bear on the resilient cup, and a clamping member secured to said threaded portion for holding said expander against said flange. 85

6. A piston construction for lubricating devices, comprising a supporting member having a threaded portion, a base carried by said threaded portion and having a centrally disposed annular flange, a resilient cup disposed on the base and having a central opening arranged to receive said annular flange, an expander having a portion disposed in engagement with said flange and being arranged to bear on the resilient cup, and a clamping member secured to said threaded portion for holding said expander against said flange. 90 95

CHARLES FREDERICK HOOFER.
